PROCESS FOR SEPARATING AND CONCENTRATING MINERALS

Maurice Constant, Scobey, Mont.

Application March 10, 1937, Serial No. 130,210

10 Claims. (Cl. 209—423)

My invention relates to processes for separating and concentrating minerals.

The objects of my invention are to afford a process by which very fine gold, silver or other mineral particles may be separated from pulp, slime, placer material or other liquid mechanical mixtures thereof, by concurrent precipitation and flotation, or by precipitation alone. My process is particularly applicable to recovery of so-called flour gold.

Various forms of apparatus may be utilized for carrying out my process. One form of apparatus suitable for that purpose is illustrated in the drawings accompanying this amendment, in which—

Figure 1 is a diagrammatic sectional elevation which illustrates an arrangement of parts of one form of apparatus for the purpose mentioned; and

Figure 2 is a diagrammatic sketch of a cross-section elevation on the line 2—2 of Figure 1.

In the drawings, 1 and 2 are the rear and front walls of a tank, and 3 and 4 are the side walls of a tank. This tank is preferably made with a height and length of approximately twelve feet and its width is preferably from one-sixth to one-quarter of its length, although the dimensions may be varied to suit the requirements of the particular placer ground to be worked.

At the front or left end of the tank is a feed hopper, 6, into which the mixture of placer ground and water is fed and from which it flows downwardly into the upper end of a riffle box, 50, which is preferably provided with a screen, 31,

35 to carry off the coarser material and through which the finer material may pass and by gravitational action the particles of metal, being heavier than the waste, will be deposited upon the bottom of the sluice which may be provided

40 with grooves, riffles, or any other suitable device for catching and advancing the particles of metal to the outlet, 41.

The riffle box is mounted upon hangers, 42, which are pivoted in the tank and may be driven 45 by a motor connected to the riffle box by a connecting rod, 68, or other suitable means.

The riffle box is preferably sloped with the rear end extending downwardly at an angle proportionate to the speed of the current and the time requisite to permit gravitational subsidence 50 and deposition of the metal particles. The larger and heavier the particles of metal, and the cleaner and clearer the mixture, the more rapid will be the subsidence and deposition, but the finer the 55 particles and the more clay or other colloidal

matter carrier in the mixture, the slower will be the subsidence and deposition. In general, a slope of from one to six inches per foot will be found practical for the commoner forms of placer material. The flow of current along the riffle box will also be governed to some extent by the rate at which the mixture is fed into the hopper or apron, 6, and the size of the opening provided by the door or gate, 84, which is slidably mounted upon the front end of the tank in position to 10 regulate the opening through which the feed must pass.

Baffle plates, 29, are provided which extend clear across the tank above the riffle box and have downward extensions which extend downwardly on both sides of the riffle box.

The purpose of these baffles is to prevent forward movement of the general body of water in the tank and to confine the current of placer material as closely as possible to the riffle box. 20 At the same time, the position of these baffles permits free upward movement of the water which may be fed to the tank through the supply pipe, 76, with openings into the bottom of the tank at 71, 71' and 71'', through which water 25 may be fed into the tank and cause an upwardly moving current at the sides of and above the riffle box. At the same time a horizontal screen, 28, is mounted in the upper part of the tank through which the water may pass and carry 30 any of the fine particles of metal having sufficient buoyancy to be floated, and such particles of metal may be raked from the screen by traveling rakes, 27, carried by the belt, 26, passing over suitable pulleys, 18 and 22. These rakes carry 35 the metal and the water floating it, to a discharge pipe, 90, from which it is discharged through the outlet, 86, into a strainer or de-waterer, 87.

A discharge opening, 41, is provided in the bottom of the riffle box through which precipitates may be discharged through the pipe, 38, and below the opening, 41, a fine screen, 32, may be mounted in the floor of the riffle box having a small compartment, 34, under the screen filled 45 with buckshot, 33, between which fine particles of metal may also lodge and from which they may be carried off and discharged through the outlet, 37, after passing through a funnel, 35, through the pipe, 36.

The lower end of the riffle box preferably extends outwardly through the rear wall, 1, of the tank and into a tailings chamber from which it may be carried by an elevator, 7, provided with buckets, 8. An overflow outlet, 10b, may be pro- 55

vided near the top of the tailings chamber and an additional outlet, 10a, may be formed in the bottom of the tailings chamber for cleanout purposes.

5 It will be understood that the apparatus shown, which is substantially that covered by my co-pending application for apparatus patent, is merely illustrative of one form of apparatus by which my process can be carried out. Various 10 other means may be devised by which a current of placer material may be subjected to pressure corresponding to the pressure existing at a substantial depth in a body of water. For instance, the mixture can be fed into a closed tank where- 15 in it may be subjected to air pressure. The form of the riffle box or sluice may have wide variations. Likewise, the vibratory movement of the riffle box may be varied or even entirely omitted.

It is well known to those skilled in the art that 20 in certain kinds of placer material some of the fine gold appears to be greasy, and either because of being mixed or coated with some greasy or oily substance, or because of certain chemical combinations, it will float or travel at or near the 25 top of a stream of fluid.

It is also well known that in some placer material, as well as in certain pulps, slimes and pulv- 30 erized ores, there will exist a percentage of metal particles too fine to readily precipitate. I have found that panning or manipulating such mix- 35 tures at a depth of several feet below the surface of a body of liquid will cause precipitation of such particles.

My process not only permits recovery of metal 35 particles too fine to be precipitated by ordinary means, but also facilitates and speeds up the subsidence and deposition of fine particles which may be recovered, although at a much slower rate by processes heretofore in use.

40 In order to carry out my process, I provide means by which the slime, pulp or other mechanical mixture of pulverized ore and water, is fed into a large, deep, tank at a considerable depth below the surface of the water or other 45 fluid therein, and is then conducted slowly over and along a riffle box at a substantial depth below the surface. Meanwhile, the riffle box is vibrated with a rapid, reciprocatory, longitudinal movement.

50 I also mount in the tank, partitions or other means extending downwardly from the surface to a short distance above the vibratory riffle box at comparatively short intervals and these partitions have the effect of preventing rapid longitudinal movement of the fluid in the tank. The sluice or 55 riffle box is inclined downwardly from the feed end at a substantial angle, preferably of from one to six inches per foot. But the pitch may be varied to suit different types or classes of material to be separated.

Extending longitudinally of the tank approxi- 60 mately at the surface level of the fluid therein contained, I mount a screen preferably of about fifteen or sixteen meshes to the inch, and extending lengthwise of the tank at about the middle thereof. I prefer to form this screen with a width approximating one-third the width of the tank and I provide doors or cover plates hinged 65 to the upper edges of the sides of the tank and adapted to extend from the sides of the tank to the edges of the screen.

A traveling rake is provided, the bars of which 70 extend transversely of the screen and travel lengthwise of the screen from the feed toward 75

the discharge end of the tank where an outlet is provided to carry off the scrapings moved by the rake.

At the bottom of the tank and below the sluice, I provide a plurality of inlets by which fresh 5 water may be constantly brought into the tank to create an upward current at the sides of the riffle box. The lower end of the riffle box extends outwardly through the foot-wall of the tank and into an elevator chamber from which 10 the accumulating tailings may be carried by a suitable elevator.

The riffle box is preferably suspended upon swinging arms which may be suitably connected by a longitudinal rod extending through a packing in the head of the tank, to be driven by a cam, crank, or other suitable means for the purpose of vibrating the riffle box. I prefer to operate, or at least to assist in operating, the riffle box in one direction by a spring which may be 15 either a tension or compression spring as circumstances make most desirable.

The riffles in the riffle box are preferably formed in the form of rectangular grooves one of which extends lengthwise along the middle of the bottom board, with diagonal grooves extending outwardly therefrom and connecting with the central groove.

The slime or mixture being led into the tank under a substantial depth of water, any metal 20 particles therein will naturally be pretty thoroughly wetted and as the current moves lengthwise of the sluice from the feed to the discharge end thereof, the gold or other mineral which is wet, being heavier than the fluid, will settle toward the sluice board and be precipitated in the 25 riffles or grooves above described, where the vibratory movement and the slope of the riffle box combined, will cause it to travel to the lower end of the central groove where a discharge pipe 30 is connected to the lower end of the groove, which 35 will carry off the precipitates.

In case any of the precipitates pass the discharge opening in the sluice, they may be caused to pass through a fine screen which is mounted 40 at the lower end of the riffle box on a level with the bottom board.

Under this screen and spaced therefrom, I 45 mount another screen and between the two screens, I place a charge of buckshot or other suitable material, adapted to permit downward 50 passage of the fines through it, and the lower screen discharges into a sloping chamber that will conduct the material from the lower screen to an outlet pipe from which it may be drawn 55 off as desired.

While the depth of the riffle box and the water level in the tank may be varied as circumstances require, I prefer to utilize a depth of from four feet to ten feet, depending somewhat upon the 60 fineness of the gold. The finer the gold is, the greater the depth should be.

Any desired form of riffle box may be used, but I prefer to use a box comprising a grooved bottom board with side boards attached thereto.

It will be noted that while my process employs the action of gravity to permit or cause the subsidence and deposition of part of the gold or other metal and the corresponding action of buoyancy or differential gravitational action to separate the fine particles which are floatable, it increases the differential action or the separative action of gravity by causing such action to be initiated and to take place at a substantial depth below the surface of the water.

It is difficult to explain why the differential action of gravity is thus increased, but the fact remains that I have discovered that such action may be thus increased and my process is applicable to any means which utilizes this increased differential action by applying substantial pressure to the mixture while flowing over and along a sluice upon which deposition of the metal by gravity is taking place or by which the lighter particles of flour gold or other metal are sought to be floated in order to separate them from such a mixture.

Various forms of apparatus may be used to carry out the process described and I do not limit my claims to the particular form of apparatus shown or described herein.

The bottom board is preferably provided with a longitudinal rectangular groove extending down the middle thereof, with oblique rectangular grooves branching out to each side therefrom and sloping downwardly toward the middle groove.

In the claims I use the term "fine gold" to apply to the fine particles of gold found in certain types of placer ground, and the term "flour gold" to apply to the superfine particles of gold some of which will settle or subside and some of which have a tendency to float or at least remain in suspension, and which will not readily subside but which will be readily carried upward in an ascending current of water; and I use the term "buoyant particles" to indicate the aforesaid particles of flour gold which will float or remain in suspension by reason of their fineness, as well as by reason of being coated or combined with any substance lighter than water, which will tend to prevent settling or subside.

The term "substantial pressure" is used in the claims to indicate such a pressure as would be produced by a head of water approximately four feet or more, it being well known that the weight of a body of water is equivalent to approximately half a pound per square inch for each foot of depth. Wherefore, a head of four feet would produce a pressure of approximately two pounds per square inch and a head of ten feet would produce a pressure of approximately five pounds per square inch.

It is also well known that such pressures are exerted by such a body of water in all directions. Therefore, when a current comprising a mixture of placer ground and water is caused to flow along or through a larger body of water at a substantial depth below the surface, it is subjected to a compressive action equivalent to the pressure per square inch developed at such a depth, and this compressive action is uniform throughout the portion of the current at a given depth. In some way, the reason for which it is difficult to discover or define, such compressive action, probably by increasing the density of the current mixture, increases the tendency of the non-buoyant gold particles therein to subside or settle, and at the same time, appears to increase the buoyancy of the buoyant particles and cause them to rise more rapidly than they would otherwise.

It is this increased tendency of the non-buoyant particles to subside or settle and this increased tendency of the buoyant particles to rise, that my process is designed to produce and effectuate, but my process is not intended to be limited to auriferous ground, gravel or pulp, but is intended to apply to all other minerals which may be found to be affected in like manner.

I am aware that riffle boxes or similar devices have been used which, in operation, were covered with water, and I am aware that means have been used such as baffles and a gradual increase in the cross sectional area of a tank or trough for the purpose of progressively retarding the flow of current therein so as to provide for a differential deposition of mineral particles. I am also aware that flotation has been used to some extent for separating buoyant particles of mineral, but so far as I am aware, no one prior to my use thereof, has made use of the process described by me of increasing the rate and quantity of gravimetric separation of both subsidable and floatable particles of mineral by subjecting a body or current of pulp or a mixture of placer ground and water to the pressure of a substantial head of water superimposed thereon varying in height in proportion to the requirements of each particular case, or of increasing the rate and quantity of flotation by utilizing a slowly moving upward current of water at both sides of and above a stream or body of pulp or an aqueous mixture of placer ground, in the presence of a superimposed body of water of considerable depth, the depth being varied proportionately to the kind, quality and condition of the mineral particles. In such cases, the best depth must necessarily be determined by tests made upon the particular material undergoing treatment, but in most cases, a depth of from four to ten feet of superimposed water will be found effective and efficient.

I claim:

1. The method of increasing the rate of subsidence and deposition of flour gold from a mixture of placer ground and water, which consists in flowing said mixture in a current confined at the sides and bottom through a relatively much larger body of confined water at a substantial depth, subjecting such current to longitudinal vibratory action beneath such current whereby the gold may be deposited by gravitational action, drawing off the precipitates and wastes by separate outlets, providing an upward flow of water at the sides of and above the current adapted to carry upward therefrom buoyant particles of gold and raking and discharging said particles.

2. The method of accelerating the gravimetric separation of fine gold and flour gold in a pulp consisting of water and auriferous ground, sand or gravel, which consists in subjecting a stream of such pulp to the continuous pressure of a body of water superimposed thereon, to a height of four feet or more, and simultaneously subjecting the buoyant flour gold to the lifting action of an upwardly moving current of water on both sides of and above such stream, withdrawing the deposits from the bed of the stream of pulp, and discharging the flour gold from the surface.

3. The process of simultaneously separating subsidable particles of gold and floatable flour gold from an aqueous pulp containing both, which consists in causing a current of such mixture to flow along a downwardly sloping trough under a superimposed body of liquid having a head of four feet or more to increase the rate of deposition of the heavier particles of gold in the trough, and simultaneously providing an upwardly moving current of water at each side of and above the trough to carry upwardly the lighter flour gold, then drawing off the deposit from the trough and raking off the flour gold from the surface.

4. The method of accelerating the gravimetric separation of fine particles of metal in a pulp

consisting of water and metal-bearing ground, sand gravel or pulp, which consists in subjecting a stream thereof to the pressure of a body of water superimposed thereon to a height of 5 four feet or more, and simultaneously subjecting the buoyant particles to the lifting action of an upwardly moving current of water on both sides of and above such stream, withdrawing the 10 deposits from the bed of the stream of pulp, and raking off the buoyant particles from the surface.

5. The process of separating flour gold and other fine gold from an aqueous mixture of auriferous earth, which consists in flowing a current of such mixture along a trough in the lower 15 part of a larger body of such aqueous mixture at a depth in excess of four feet below the surface, retaining the larger body of the liquid against forward movement to allow subsidence 20 and deposition of gold particles by gravitational action along the bottom of such trough, withdrawing such deposit from the trough, providing an upward flow of water at the sides of and above the trough to carry upward buoyant particles of 25 gold therein, and raking off and discharging such buoyant particles and then de-watering them through a suitable filter.

6. The process of separating fine particles of metal from a metal-bearing pulp which consists 30 in flowing a current of such pulp mixed with water along a trough in the lower part of a larger body of water at a depth in excess of four feet below the surface, retaining the larger body of the liquid against forward movement to allow 35 subsidence and deposition of such particles by gravitational action along the bottom of such trough, withdrawing such deposit from the trough, providing an upward flow of water at the sides of and above the trough to carry upward buoyant particles of metal 40 therein, and raking off and discharging such buoyant particles and then de-watering them through a suitable filter.

7. The process of separating flour gold and other fine gold from an aqueous mixture of auriferous earth, which consists in subjecting a current of such mixture flowing along a trough to the continuous pressure of a superimposed body of such mixture in excess of two pounds per 45 square inch, retaining the superimposed liquid against forward movement to allow deposition of 50 subsidable gold particles by gravitational action along the bottom of such trough, withdrawing

such deposit from the trough, providing an upward flow of water at both sides of the trough to carry upwardly to the surface buoyant particles of gold, and raking off and discharging such buoyant particles and then de-watering them 5 through a suitable filter.

8. The process of separating fine particles of metal from a metal-bearing pulp which consists in subjecting a current of such mixture flowing along a trough to the continuous pressure of a 10 superimposed body of such mixture in excess of two pounds per square inch, retaining the superimposed liquid against forward movement to allow deposition of subsidable metal particles by gravitational action along the bottom of such 15 trough, withdrawing such deposit from the trough, providing an upward flow of water at both sides of the trough to carry upwardly to the surface buoyant particles of metal, and raking off and discharging such buoyant particles 20 and then de-watering them through a suitable filter.

9. The process of separating flour gold and other fine gold from an aqueous mixture of auriferous earth, which consists in flowing a current 25 of such mixture along and through a larger body of such aqueous mixture, at a depth in excess of four feet below the surface, retaining the larger body of the liquid against forward movement to allow subsidence and deposition of gold 30 particles by gravitational action, withdrawing such deposit and the tailings, providing an upward flow of water at the sides of and above the current to carry upward buoyant particles of gold 35 therein, and raking off and discharging such buoyant particles and then de-watering them through a suitable filter.

10. The process of separating fine particles of metal from a metal-bearing pulp which consists in flowing a current of such mixture along and 40 through a larger body of such aqueous mixture, at a depth in excess of four feet below the surface, separating the tailings from the metal, retaining the larger body of the liquid against forward movement to allow subsidence and deposition 45 of such particles by gravitational action, withdrawing such deposit and the tailings, providing an upward flow of water at the sides of and above the aforesaid current to carry upward buoyant particles of metal therein, and raking off and 50 discharging such buoyant particles and then de-watering them through a suitable filter.

MAURICE CONSTANT.
